US00D632309S

(12) **United States Design Patent**
Coyle, Jr.

(10) **Patent No.:** **US D632,309 S**
(45) **Date of Patent:** **** Feb. 8, 2011**

- (54) **DOWNHOLE MAGNET JET TOOL**
- (75) Inventor: **William E. Coyle, Jr.**, Houma, LA (US)
- (73) Assignee: **Bilco Tools, Inc.**, Houma, LA (US)
- (**) Term: **14 Years**
- (21) Appl. No.: **29/360,939**
- (22) Filed: **May 3, 2010**
- (51) LOC (9) Cl. **15-03**
- (52) U.S. Cl. **D15/21**
- (58) **Field of Classification Search** **D15/21; 175/57, 325.1, 320, 327, 424; 15/104.05, 15/104.09, 104.2, 181, 122**

See application file for complete search history.
